UNITED STATES PATENT OFFICE.

HOLSTEIN W. WEBB, OF COLUMBUS, OHIO.

MANUALLY-CONTROLLED GAS-BURNER AND PILOT-LIGHT.

SPECIFICATION forming part of Letters Patent No. 737,305, dated August 25, 1903.

Application filed May 8, 1902. Serial No. 106,455. (No model.)

To all whom it may concern:

Be it known that I, HOLSTEIN W. WEBB, a citizen of the United States, residing at Columbus, in the county of Franklin and State 5 of Ohio, have invented a certain new and useful Improvement in Manually-Controlled Gas-Burners and Pilot-Lights, of which the following is a specification.

My invention relates to the improvement 10 of gas-burners and pilot-lights therefor, and has particular relation to the improvement of the construction shown and described in my former application for patent, Serial No. 105,604, filed May 2, 1902.

15 The objects of my present invention are to provide a simple and effective valve mechanism and means for operating the same by hand, to provide in conjunction therewith improved means for conducting gas from the 20 main supply-pipe to the pilot-tube, and to produce other improvements, the details of which will be more fully pointed out hereinafter. These objects I accomplish in the manner illustrated in the accompanying drawings, 25 in which—

Figure 1 is a view in elevation of a portion of a gas-pipe having my improvements and showing in connection therewith illuminating and pilot burners. Fig. 2 is a view of a 30 portion of said gas-pipe, taken at right angles with that shown in Fig. 1. Fig. 3 is an enlarged transverse section through the valve, taken on line $x-x$ of Fig. 1; and Fig. 4 is a central vertical section through the valve- 35 containing portion or section of the gas-supply pipe.

Similar numerals refer to similar parts throughout the several views.

In carrying out my invention I employ a 40 gas-conducting pipe-section 1, the upper end of which may be suitably connected with an ordinary gas-supply pipe. Running longitudinally through the section 1 are comparatively large and small gas-passages 2 and 3.

45 With the lower end of the section 1 is suitably coupled a short downward gas-conducting pipe-section 4, the lower end of which is formed or provided with a cap 5. Leading laterally from the pipe-section 4 are the desired number of burner-supporting pipe-arms 6, from the outer ends of which rise suitable illuminating gas-burners, one of which is in-

dicated at 7. That portion of the lower end of the pipe-section 1 through which extends the passage 3 has connected therewith the 55 upper end of a gas-conducting tube 8, which extends downward within and through the section 4 and which within the end cap 5 communicates with an outwardly-extending pilot-burner-tube-supporting arm 9, from 60 which rises the pilot-tube 10, the latter having a suitable burner-head 11.

Within a transverse conical socket which intersects the pipe-section 1 I provide a rotatable conical valve 12, the latter having 65 formed through its larger end portion a diametric opening 13, which is adapted to be brought into communication with the passage 2, while the smaller end portion of the valve is provided on opposite sides with separated 70 peripheral grooves or gasways 14. From these grooves 14 lead to the opening 13 valve-surface grooves 15. The valve 12 is provided at its smaller end with a short outwardly-extending and peripherally-grooved stem 16, 75 with which is adapted to engage the upper end of a spring-strip 17, the lower end of which is secured to the outer surface of the pipe-section 1, this valve-plug strip serving to hold the spring against withdrawal from 80 its seat. The larger outwardly-projecting end of the valve is provided with a reduced extension 18, on which is carried inner and outer ratchet-wheels 19 and 20, the teeth of which project in opposite directions. Secured 85 to the outer surface of the pipe-section 4 at a point below the ratchet-wheels 19 and 20 is the lower and inturned end of an upwardly-extending bracket-screw 21, upon the threaded portion of which is carried a nut 22. Above 90 this nut said screw is flattened and has pivoted thereto a lever-bar 23. This lever-bar has its outer end connected with the bracket 21 through the medium of a spring 24 and at its remaining end has depending therefrom an operating chain or cord 25. The spring 24 serves to normally depress the outer end of the lever until the latter is in contact with the nut 22, and this depressed end portion of said lever is provided with an upwardly-projecting pin 26. The normally elevated end portion of the lever is provided with an upwardly-extending pawl-arm 27, the upper hook end of which is adapted to suc-

cessively engage the teeth of the inner ratchet-wheel 19. Leading into the body of the pipe-section 1 and having its inner end adapted to enter the passage 3 is a regulating-screw 27.

In order to illustrate the operation of my device, we will assume that the valve 12 is turned to the position indicated in Fig. 4 of the drawings, in which position the passage 3 is in communication with the central portions of the oppositely-located valve-grooves 14, and that the passage 2 is closed from the fact that it is intersected by the imperforated portions of the valve. It will be observed, however, that the gas-supply through the passage 3 and the upper groove 14 will be carried through one pair of the grooves 15 to the main valve-opening 13, thence through the remaining grooves 15 to the under side groove 14, down through the continuation of the passage 3, thence through the pipe 8, pipe-arm 9, and pilot-tube 10 to the pilot-burner 11. The limited supply of gas thus furnished the burner-head of the pilot-tube is adapted to maintain a comparatively small light at said burner-head. By pulling downward on the chain 25 until the pin 26 comes into contact with a tooth of the outer ratchet-wheel 20 and a partial rotation is imparted to the inner wheel 19 the valve 12 is rotated sufficiently to open communication between the main passage 2 and valve-opening 13. Owing to the extent of the recesses 14 communication of the passage 3 with said recesses is not cut off by said partial rotation of the valve. As a result of the above-described operation of said valve not only is gas furnished through the passage 2 to the illuminating-burners 7, but an increased gas-pressure is provided in the lower portion of the passage 3 through the groove connection 15 of the lower valve 14 and the main valve-opening 13. This increased supply of gas to the passage 3 and pilot-tube burner 11 results in extending the flame at the pilot-burner head and insuring the lighting therefrom of the gas which is escaping from the heads of the burners 7. This operation being accomplished and the lever-bar having been allowed to assume its normal position, a second pull on said lever-bar results in a second partial rotation of the valve, whereby the valve-grooves 14 are thrown out of communication with the passage 3, although the main valve-opening 13 still remains in communication with the passage 2, owing to the size of said valve-opening. By this operation it will be observed that gas will be cut off entirely from the pilot-tube, while the flames at the illuminating burner-heads will continue. A third operation of the valve-controlling lever results, in the manner heretofore described, in another partial rotation of the valve, which again brings the passage 3 into communication with the valve-grooves 14 and results in the gas at the burner-head of the pilot-tube igniting. A fourth operation of the valve-lever so turns the valve as to cut off communi-

cation between the passage 2 and valve-opening 13, thereby extinguishing the lights at the burners and leaving a comparatively small flame at the pilot-burner.

By this construction and operation it will be seen that simple and effective means are provided for manually controlling the supply of gas at the pilot and illuminating burner heads and that owing to the arrangement of the gas-conducting tube 8 within a section of the main supply-pipe the pilot supply-tube is hid from view, and this is accomplished without interfering with the passage of the gas from the supply-pipe into the burner-arms 6.

Having now fully described my invention, what I claim, and desire to secure by Letters Patent, is—

1. In an apparatus of the character described, the combination of a gas-burner having a main supply-passage, a pilot-burner having a supplemental supply-passage located externally and at one side of the main passage, and a turning plug piercing both passages and provided with a diametric opening to register with the main passage, diametrically opposite peripheral grooves, located in a plane wholly at one side of the plane of the opening to register with the supplemental passage, and longitudinal grooves communicating between the ends of the diametric opening and the corresponding ends of the respective peripheral grooves. 85

2. In an apparatus of the character described, the combination of a gas-burner having a main supply-passage, a pilot-burner having a supplemental supply-passage, a turning plug piercing both passages and provided with means for successively maintaining either passage closed and the other open and for opening both passages and establishing a communication from the main passage to the supplemental passage, a pair of reversely-disposed ratchet-wheels upon the plug, and an intermediately-fulcrumed controlling-lever having a pivotal ratchet-dog in co-operative relation with one of the ratchet-wheels, and a push projection in co-operative relation with the other ratchet-wheel. 105

3. In a burner, the combination of a turning plug, a pair of reversely-disposed ratchet-wheels carried by the plug, a screw-threaded pin carried by the burner, a lever intermediately fulcrumed upon the pin, a nut adjustable upon the pin and lying in the path of the lever to form an adjustable stop therefor, a pivotal ratchet-dog carried by the lever for one of the ratchet-wheels, and a push projection upon the lever for the other wheel. 115

4. In an apparatus of the character described, the combination of a main gas-chamber having a radial series of gas-burners connected thereto, a supply-pipe connected to the chamber and provided with a main passage and a smaller supplemental passage, a pilot-burner connected to the supplemental passage and in close proximity to one of the series of burners, a turning plug 13

piercing the main and supplemental passages, and provided with a diametric opening to register with the main passage, opposite peripheral grooves to register with the supplemental 5 passage and longitudinal grooves communicating between the ends of the diametric opening and the corresponding ends of the respective peripheral grooves, spaced reversely-disposed ratchet-wheels upon one end of the 10 plug, a bracket upon the burner, a spring-actuated lever fulcrumed intermediately upon

the bracket, a ratchet-dog pivoted upon the lever at one side of the fulcrum thereof and a coöperative relation with one of the ratchet-wheels, and a push projection upon the lever 15 at the opposite side of the fulcrum and in coöperative relation with the other ratchet-wheel.

HOLSTEIN W. WEBB.
